United States Patent Office

Des. 183,160

Patented July 8, 1958

183,160

TEXTILE FABRIC OR SIMILAR ARTICLE

Sergei Bogdanovich, Carmel, N. Y., assignor to Weil & Durrse, Inc., New York, N. Y., a corporation of New York

Application August 1, 1957, Serial No. 47,188

Term of patent 7 years

(Cl. D92—1)

The figure is a face view of a textile fabric or similar article, showing my new design. The full width of the fabric is disclosed vertically, and an end of the fabric is shown at the left. The design unit is repeated horizontally, as indicated by the broken line at the right.

I claim:

The ornamental design for a textile fabric or similar article, substantially as shown and described.
